UNITED STATES PATENT OFFICE.

JOSEPH FRUMVELLER, OF CHICAGO, ILLINOIS, ASSIGNOR TO VAPOR CAR HEATING COMPANY, INC., OF CHICAGO, ILLINOIS, A CORPORATION OF NEW YORK.

WATER HEATER.

Application filed July 1, 1920. Serial No. 393,301.

To all whom it may concern:

Be it known that I, JOSEPH FRUMVELLER, a citizen of the United States, residing at Chicago, in the county of Cook and State of Illinois, have invented certain new and useful Improvements in Water Heaters, of which the following is a specification.

My invention relates to a water heater of the character used in railway car water heating systems; a heater of this type consisting of a stove having arranged within the fire box thereof two water coils which are substantially helical. It has been usual to form the coils with the turns or spirals curved in the same direction, that is, with both coils right helixes or both left helixes, and to dispose them in the fire box with the spirals or turns in alternate arrangement one above the other, that is to say, with the axes 10 of the helixes coincident. My invention contemplates a different construction and disposition of the coils. I employ two coils, one in the form of a right helix and the other in the form of a left helix, that is, one coil is 15 curved to the right from one of its terminal portions and the other is curved to the left from corresponding terminal portion; and instead of having the axis of one coil coincide with the axis of the other coil I dispose 20 the coils in offset or staggered relation to each other, one being nearer the other side. As a result certain important advantages are obtained: First, the efficiency of the heater is increased by the staggering of the coils 25 since the coils in this staggered relation are better exposed to the combustible gases than in the old form of heater where the coils had a common axis, and since the coils, as will be explained hereafter, may be arranged 30 lower down in the fire box without interfering with the tilting of the grate when the latter is dumped; second, the manufacture of the coils is facilitated since it is not necessary to form the lower terminal portions of 35 the coils, that is to say, the portions of the pipes which extend to and through the wall of the stove with the usual double bends, lateral and upward, which have been necessary in heaters of this type as formerly constructed in order to avoid interference with the grate and the formation of which required great care in order that the terminals might be properly aligned with the openings made in the wall of the stove and 40 45 50 55 in order that there might be as little cross

sectional deformation of the pipes at the bends as possible. Even with the most careful workmanship some deformation at the bends or offset portions of the coils was inevitable and this it may be said, by diminishing the cross sectional areas at the places of bend necessarily impeded the flow of water through these portions of the pipes. 60

The invention is illustrated, in a preferred embodiment, in the accompanying drawing wherein

Fig. 1 is a vertical sectional view illustrating a water heater constructed in accordance with my invention. 70

Figs. 2 and 3 are sectional plan views on lines 2—2 and 3—3 of Fig. 1, and

Fig. 4 is a view, in perspective, of the two coils showing their configuration and arrangement with relation to each other. 75

Referring to the drawing, 10 designates the body of the stove which may be of any desired construction. The interior of the stove is divided by grate 11 into a combustion chamber 12 and an ash pit 13, 14 80 indicating the door of the ash pit. 15 is the smoke outlet of the stove and 16 the coal magazine, the stove herein shown for purpose of illustrating the application of my invention to practical use being of the base 85 burner type. The grate 11 is shown as supported on the usual rocker 17 so that it may be tilted for dumping, the edge of the grate adjacent the ash door 14 tilting downwardly and the opposite edge upwardly. The grate 90 is arranged within a circular opening in the conical member 18 at the bottom of the fire box.

Within the fire box 12 are arranged two water coils A and B, one in the form of a right helix and the other in the form of a left helix, these coils being formed with upper terminal portions 19 and 20 and lower terminal portions 21 and 22 which extend through openings in the wall of the stove 100 and are connected with the water circulatory system of the car heating apparatus (not shown). The coils are disposed with their turns or spirals in alternate arrangement, one above the other, but the axes of 105 the coils are not coincident, one coil being offset to one side of the stove and the other coil to the other side thereof. This allows the curved portions 23, 24 of the lower turns of the coil which are adjacent to 110

terminals 21, 22, respectively, to lie close to the inner surface of the stove wall, that is, directly above the conical bottom 18 so that they do not interfere with the tilting 5 of the grate 11 even when the coils are arranged just above the conical bottom 18. That is, the back edge of the grate in tilting will pass up between the coils. For this reason it is possible to arrange the coils 10 lower down in the stove, and consequently deeper in the fire, than could be done in the old form of heater. Preferably the first quarter, approximately, of each lower turn (the portion designated by numeral 15 23 or 24) extends horizontally, the coils beginning to bend upwardly from points indicated by numerals 25, 26. This facilitates the manufacture of the coils since the bends at 25, 26 are removed at some distance 20 from the lateral bends 27, 28 necessary for bringing the terminals of the coil out through the wall of the stove. In the old type of heater one or both of the coils had to be formed with a sharp upward bend 25 or offset close to the lateral bend and this double bending or offsetting of the pipe involved difficulties of manufacture, as stated above, and also resulted in impeding 30 the water circulation through the heater since some cross sectional deformation of

the pipe at the place of offsetting was inevitable. Moreover, the upward offset necessary to give clearance for tilting the grate resulted in raising the coil in the stove by just so much, thereby diminishing the 35 amount of heat applied to the coil since the heat derived from direct contact of the burning coal is greater than that received by the upper portion of the coil from the gases of combustion. The staggered arrangement 40 of the coils gives better distribution of the water pipes in the fire box and thus increases the heating efficiency of the device.

I claim:

A water heater comprising a fire box to 45 contain a solid fuel, a grate at the bottom of the fire box arranged to tilt upwardly into the fire box at the back of the heater and a pair of water coils in the fire box in the form of right and left helixes with their 50 axes offset laterally with respect to each other and their turns in alternate arrangement one above the other, said coils having lower terminals extending through the wall of the heater at the back thereof and lower 55 turns arranged close to the grate so that the back of the grate in tilting may pass between them.

JOSEPH FRUMVELLER.
